UNITED STATES PATENT OFFICE.

WILLIAM T. WELSH, OF CINCINNATI, OHIO.

VALVE OR FAUCET.

SPECIFICATION forming part of Letters Patent No. 761,433, dated May 31, 1904.

Application filed December 6, 1902. Serial No. 134,122. (No model.)

To all whom it may concern:

Be it known that I, WILLIAM T. WELSH, a citizen of the United States of America, and a resident of Cincinnati, in the county of Hamilton and State of Ohio, have invented certain new and useful Improvements in Valves or Faucets, of which the following is a specification.

This invention relates to certain improvements in valves or faucets, such as are adapted for controlling the flow of fluids through passages; and the object of the invention is to provide a device of this character with auxiliary means for controlling the flow of fluid independently of the control exercised through the medium of the main valve, so that the escape of fluid past the main valve is prevented when said main valve is removed for repairs. The auxiliary controlling means also permits of regulating the pressure of the fluid in flowing past the main valve, so that damage due to sudden checking of the flow at the main valve is prevented.

The invention consists in certain novel features of the construction, combination, and arrangement of the several parts of the improved valve or faucet whereby certain important advantages are attained and the device is made simpler, cheaper, and otherwise better adapted and more convenient for use, all as will be hereinafter fully set forth.

The novel features of the invention will be carefully defined in the claim.

In the accompanying drawings, which serve to illustrate my invention, Figure 1 is a side elevation of a valve or faucet constructed according to my invention, and Fig. 2 is an axial section taken through the valve or faucet and showing the main valve and auxiliary controlling means thereof. Fig. 3 is a view similar to Fig. 2, but showing the main valve in opened position and the auxiliary controlling means adjusted in position for reducing the fluid-pressure within the casing of the valve or faucet.

As shown in these views, the improved valve or faucet embodying my improvements is provided with a casing or body portion 1, having at one side a screw-threaded extension 2 projecting from it and adapted for connection

with a service-pipe, (not shown,) said extension 2 being formed with a bore or passage 3, through which the fluid is adapted to flow from said service-pipe into the hollow interior or chamber of the main or body portion of the 55 valve or faucet casing 1.

4 indicates a partition extended transversely and horizontally across the interior hollow or chamber of the main or body portion of the casing 1, and said partition 4 serves to divide 60 said chamber into a lower compartment 5, with which the passage or bore 3 has free communication for the supply of fluid, and an upper compartment 6 above said partition, communication between the lower and upper compartments 5 and 6 being afforded by way of 65 a port 7, formed in said partition 4. At the side opposite to the extension 2 the casing 1 of the valve or faucet is provided with a discharge-nozzle 8, having a bore or passage 9, 70 adapted for communication with the upper compartment 6 for the discharge of fluid from the casing.

The partition 4 is provided with two valve-seats, one of which is indicated at 10 and is 75 ground to a conical form upon the lower or under side of said partition and within the lower compartment 5, being concentric around the port 7 in the partition. The other valve-seat is indicated at 11 and is made in raised 80 annular form within the upper compartment 6 and upon the upper surface of the partition and is also concentric with respect to the port 7 in said partition.

The casing 1 of the valve or faucet is provided at its upper part with an upwardly-extended boss or extension 12, the interior of which is in communication with the upper compartment 6 in the casing and the external wall of which is screw-threaded to receive a 85 screw-cap 13, between which and the upper edge of said boss or extension 12 is held a gasket or packing-ring 14, of rubber or other suitable material. The lower interiorly-screw-threaded portion of the cap 13 is made in 90 hexagonal form, so as to be capable of ready removal by means of a wrench or other tool, and said cap is provided with a reduced and interiorly-screw-threaded neck 15 at its upper 95 part, within which is arranged to screw a 100

valve-stem 16, having screw-threads for engagement in said interior screw-threads of the neck 15, as shown at 17, and also provided at its lower end with a head or enlargement 18, held upon it, which head or enlargement carries a flat valve 19, of rubber or other suitable substance, adapted when the valve-stem 16 is turned to be moved toward and away from the upper raised valve-seat 11, the stem 16 being axially alined above the port 11, so that the valve 19 may fit snugly upon said seat 11 when the stem is screwed down into the casing. The stem 16 is provided at its upper end with a handle 20 of any preferred kind, and in order to prevent the escape or leakage of fluid around the stem in case the screw-threads thereof should not properly correspond with those of the neck 15 I provide said neck 15 with exterior screw-threads 21 whereon is engaged an auxiliary cap 21, adapted to hold a packing 22 to produce a tight joint around the upper part of the valve-stem 16.

The lower part of the casing 1 of the valve 25 or faucet is also provided with a downwardly-extended nipple or boss 24, which is exteriorly screw-threaded to receive a screw-cap 25, within which is held a packing-ring or gasket 26 for producing a tight joint at the 30 lower edge of said nipple or boss. The nipple or boss 24 is also provided with interior screw-threads, with which is engaged a screw-threaded part 27, produced upon a lower auxiliary-valve stem 28, the upper end of 35 which carries a cone-shaped valve 29, adapted to fit the valve-seat 10 upon the under side of partition 4 and within the lower compartment 5 of the casing, the lower end of said stem 28 being extended through the screw-cap 25 and 40 having a handle 30 of any desired kind below the same.

The lower or auxiliary valve 29 and its valve-stem 28 are arranged in axial alinement with the upper or main valve 20 and its valve-stem 16, and the construction is such that either of said valves may by turning movement of its valve-stem be adjusted nearer to or farther from its valve-seat or may be pressed closely upon its valve-seat, so that 45 either one of said valves may be employed for controlling the flow of fluid through the port 7.

The valve-stem 28 of the lower or auxiliary valve 29 is formed at its junction with the 55 enlarged screw-threaded part 27 with a gradually enlarged or tapered portion 31, as shown in Figs. 2 and 3, and on the said valve-stem 28 below said tapered portion is held an annular packing-ring or annulus 32, which when 60 the valve 29 is drawn downward by turning movement which causes the part 27 to traverse the screw-threads in the nipple or boss 24 is clamped between said enlarged screw-threaded part 27 and the packing 26 at the base of the screw-cap 25, the expanded or tapered portion 65

31 of the valve-stem being at the same time pressed into close contact with the central opening in said packing-ring 32 in such a way as to produce a tight joint and prevent leakage at the base of the casing. In this way it 70 will be seen that by drawing the auxiliary valve down tightly to compress the packing below it leakage at that point may be effectually prevented, so that repairs of the auxiliary valve are not required.

In the use of the improved valve or faucet constructed according to my invention the upper or main valve 20 is normally employed for controlling the flow of fluid through the passages from the service-pipe, the lower or auxiliary valve 29 being left normally open; but when it is necessary to repair the upper or main valve, or in case said main valve should become so worn in use as to permit escape of fluid past it, the lower or auxiliary valve 29 is operated 80 and by engagement upon its seat 10 serves to effectually cut off the flow of liquid through the passages. When the lower or auxiliary valve 29 is in closed position, the flow of fluid through the valve or faucet being completely 90 cut off thereby, the removal of the main valve and its stem by the unscrewing of the cap 13 is permitted, so that ready access may be had to all of the parts above the partition 4 for purposes of repair.

Since the lower or auxiliary valve is but seldom used, it will be evident that there will be but little wear upon it, so that it will not require repairing except in case of accident or after long service. Said lower or auxiliary valve is also capable of use for regulating the pressure with which the liquid may escape through the port 7 in partition 4, since it can be adjusted to stand more or less closely adjacent to its seat 10, as indicated in Fig. 3 of 105 the drawings. In this way the strains exerted by the fluid upon being suddenly checked at the main valve may be regulated, so that damage to the parts may be avoided. It will also be seen that when the auxiliary valve is 110 screwed down tightly away from its seat it will act to clamp the packing held upon its stem in such a way as to effectively prevent leakage at this point even after the parts shall have been considerably worn. In this 115 way repair of the auxiliary valve is avoided and a material advantage is thereby attained, since to repair said auxiliary valve would necessitate shutting off the water-supply to the service-pipe with which the valve or faucet is 120 connected.

The improved valve or faucet constructed according to my invention is of an extremely simple and inexpensive construction and is very light, strong, and durable, and by its 125 use permits a considerable economy, since it permits of dispensing with the extra cock or valve commonly provided in the service-pipe, and also obviates the use of extra joints, such as are required for connecting such extra cock 130

or valve in the service-pipe, the cost of such extra cock and joints, together with the labor involved in putting them in position, being greatly in excess of the increased cost of the 5 valve or faucet provided with my improvements. Moreover, the auxiliary valve in my improved construction is always ready and in convenient position for use, so that the annoyance due to leakage, and consequent dripping 10 of the liquid from the discharge-nozzle, may be easily prevented.

The arrangement of the device with the valves and their stems in axial alinement and working against valve-seats at opposite sides 15 of a single partition in the valve-casing also permits of constructing the device in a very compact, light, and inexpensive manner.

The improved valve or faucet is also well adapted for use upon range or kitchen boilers 20 in lieu of the lower discharge-faucet ordinarily provided, and when so used the auxiliary valve may be turned to closed position when it is desired to repair the main valve, so that wasting of the water contained in the boiler 25 and loss of time and annoyance occasioned in refilling said boiler are avoided.

From the above description it will be seen that the invention is not limited in its application to valves or faucets constructed with 30 discharge-nozzles, but may as well be used in connection with valves or cocks of other constructions, and for this reason I do not wish to be understood as limiting myself to the employment of my improvements in connection 35 with discharge-faucets alone.

Having thus described my invention, what I claim, and desire to secure by Letters Patent, is—

A device of the type set forth comprising a 40 casing having a partition dividing the same

into upper and lower compartments, said partition being formed with a part surrounded on the upper and lower faces respectively of the partition with valve-seats, an internally-threaded nipple formed integral with the under side of the casing and being in communication with the lower compartment and having an interior of less diameter than that of the said lower compartment, a valve operating in the upper compartment and being adapted 45 to engage the upper valve-seat, a stem projecting through said nipple and having an enlarged portion threaded and engaging the threaded interior of said nipple, a valve on the inner end of said stem, said valve being 50 of less diameter than the enlarged portion of said stem, a cap on the lower end of said nipple, a gasket arranged in said cap and engaging the lower end of the nipple, and a second gasket superimposed on said first-named gasket and being arranged in said nipple, said stem from its enlarged portion being gradually reduced in diameter whereby an inclined portion which is arranged in said last-named gasket is provided, said inclined portion of 55 said stem being located at the upper face of the second-named gasket, so as to compress the latter into the opening of the first-named gasket when the valve is in its lowermost position, said second-named gasket on its lower 60 face adjacent the stem having a tapered portion snugly embracing the stem, substantially as and for the purpose specified.

Signed at Cincinnati, Ohio, this 26th day of November, 1902.
